UNITED STATES PATENT OFFICE.

STEPHEN A. DOBYNE, OF ST. LOUIS, MISSOURI, ASSIGNOR TO CHAMPION SHOE MACHINERY COMPANY, OF ST. LOUIS, MISSOURI, A CORPORATION OF MISSOURI.

HEATING SYSTEM FOR WAX-THREAD SEWING-MACHINES.

1,391,048.

Specification of Letters Patent. Patented Sept. 20, 1921.

Application filed February 10, 1917. Serial No. 147,941.

To all whom it may concern:

Be it known that I, STEPHEN A. DOBYNE, a citizen of the United States, and residing at St. Louis, Missouri, have invented a certain new and useful Improvement in Heating Systems for Wax-Thread Sewing-Machines, of which the following is a specification.

This invention relates to wax thread sewing machines, and more particularly, to a heating system therefor.

In the operation of a wax thread sewing machine, it is necessary that the wax thread and the devices which handle the thread be heated, in order to keep the wax and the thread in proper condition, and in order that the thread handling devices may operate satisfactorily. Where a heating flame is used to heat the thread handling devices, this flame is liable to have a destructive effect on the mechanism and overheat or burn the wax on the thread or in the wax pot. It is, therefore desirable that the thread handling devices be heated uniformly and sufficiently to keep the thread and the thread handling devices in proper condition, but not to overheat the same.

Some of the objects of this invention, therefore, are to provide a heating system for wax thread sewing machines, which is electrically controlled, and in which this electrically controlled heating means is so constructed and arranged as to heat the thread and the thread handling devices uniformly, but with the smallest consumption of energy.

Further objects will appear from the detail description taken in connection with the accompanying drawings, in which:

Figure 1 is a front elevation of a sewing machine embodying this invention;

Fig. 2 is a side elevation; and

Fig. 3 is a section on the line 3—3, Fig. 1.

In the accompanying drawings, the system is shown as applied to the machine shown and described in U. S. Patent No. 1,198,627, granted Sept. 19, 1916, and similar parts are indicated by similar reference characters, as in said application.

Referring to the drawings, 9 designates a machine head having mounted therein a drive shaft 10 supporting cams 12, 13 and 14 adapted to operate the various parts of the machine. The machine head has a for-

wardly projecting part or lug 8, which is provided with bearings and forms a support or carrier for the various parts hereinafter described. This forwardly projecting part has mounted thereon a work table 15, a co-operating presser foot 16, an awl 17, a needle 18, and a looper 19, comprising the stitch forming mechanism. The shuttle is shown at 20, and is mounted in a shuttle casing 200 on the carrier 8. A take-up shaft 27, mounted in bearings in the carrier 8, has a take-up arm 28 provided with a truck or roller 72 engaging the needle thread 51, and in this part 8 is also mounted a thread tension 30 controlled by a brake 36. Also mounted on the part 8 is an auxiliary take-up or tension 42. All of these parts are fully described in the application referred to, to which reference is had for further details of construction.

Mounted on or formed integral with the carrier 8 is a wax pot 7 having a cover 70, and also mounted on this carrier 8 is an auxiliary tension 71. The needle thread 51 passes through an eye 73 and hence through the tension 71 downwardly through the wax pot, around the tension 30, the auxiliary take-up 42, the take-up roll 72, the looper 19, and through the usual slot in the work table 15.

Formed on the forwardly projecting part 8 is a boss 6 which is bored to removably receive an electrical resistance coil 5, which is in the form of a cartridge, and which may be of usual construction, the electrical connections to this coil being shown at 4. The shuttle casing 200 has also attached thereto or formed integral therewith a metallic boss 2, which is also bored to receive an electrical resistance heating element 1, similar to 5, the electrical connections to this element or coil 1 being shown at 0. The heating elements 1 and 5 are removably mounted in their bosses, so as to be replaceable, and it will be noted that, when in position, they are inclosed by the metallic bosses, and, therefore, make a thermal conducting connection with the carrier 8 of the machine head. The take-up arm 28 has mounted therein a head 3 which may be formed integral with the truck or roll 72, or may be loosely mounted on the same stub shaft therewith, and this head engages the side face of the carrier 8 which is machined to

form a smooth bearing surface. The auxiliary take-up 42 similarly has a sliding conducting connection with the side face of the part 8.

- 5 When current passes through the resistance elements 5 and 1, heat will be generated, and this heat will be conducted to the forwardly projecting carrier 8 of the machine head. On account of the metal surrounding 10 these heating elements, and the bulk of metal, this metal bulk will act to store a considerable amount of heat and distribute the heat uniformly through the body of the carrier 8. This heat will, therefore, be applied uniformly to the wax pot, the tensions, the take-ups and the shuttle. In the case 15 of the tensions and the shuttle, the latter are practically in direct metallic contact with the metal bulk of the machine head. 20 In the case of the long take-up, the sliding connection between the truck or roll and the machine face will furnish an efficient conducting connection. The result, therefore, is that all of the thread handling 25 devices will be heated uniformly and efficiently, with the minimum amount of electrical energy, and by proper proportioning of the heating elements, the heat generated and conducted to the thread handling devices 30 is sufficient for the purposes required.

It is obvious that various changes may be made in the details of construction without departing from the spirit of this invention, and it is, therefore, to be understood that 35 this invention is not to be limited to the specific construction shown and described.

Having thus described the invention, what is claimed is:

1. In a wax-thread sewing machine, having a machine head and having thread controlling mechanism including a take-up member having a thread-engaging part, the employment of a metallic carrier mounted on said head and supporting said member, 40 said member having a linearly sliding thermal contact with said carrier, and electrical resistance heating means mounted on and in thermal contact with said carrier and adapted to heat said member through its 45 sliding contact with said carrier.
2. In a wax-thread sewing machine, having a machine head and having thread con-

trolling mechanism including a take-up member, the employment of a metallic carrier mounted on said head and pivotally 55 supporting said member, said member having at its free thread engaging end a sliding thermal contact with said carrier, and electrical resistance heating means mounted on and in thermal contact with said carrier 60 and adapted to heat said member through its sliding contact with said carrier.

3. In a wax-thread sewing machine having a machine head and having a movable thread controlling member, a metallic carrier mounted on said head, a pivot adapted to support said member on said carrier, and an element making sliding thermal contact with said carrier adapted to convey heat to 70 said member.

4. In a wax-thread sewing machine having a machine head and having a movable thread controlling member, a metallic carrier mounted on said head and having a plane face, means for movably supporting said 75 member on said carrier, and contact means for conveying heat from said face to said member.

5. In a wax-thread sewing machine having a machine head and having a movable 80 thread controlling member, a metallic carrier mounted on said head and having a plane face, means for movably supporting said member on said carrier, and an element making sliding thermal contact with said 85 face adapted to convey heat to said member.

6. In a wax-thread sewing machine, a heat distributor, means for heating said distributor, a movable thread controlling member, and a contact element mounted on said 90 member and making linearly sliding thermal contact with said distributor in order to heat said member.

7. In a wax-thread sewing machine, a heat distributor having a plane face, means for 95 heating said distributor, a movable thread controlling member, and a contact element mounted on said member and making linearly sliding thermal contact with said face in order to heat said member.

In testimony whereof I affix my signature this 11th day of July, 1916.

STEPHEN A. DOBYNE.
